Application January 4, 1939, Serial No. 249,222
In Germany January 4, 1938

7 Claims. (Cl. 179—171)

This invention relates to amplifying circuit arrangements for amplifying a given frequency band, particularly wide frequency bands including the low frequencies, in such a manner that the amplification is independent of frequency so that uniform amplification throughout the band is obtained.

Wide band amplifiers having uniform amplification or frequency-independent characteristics are of considerable importance in electrical arts and especially in television. Hitherto the construction of such amplifiers have been exceedingly difficult and costly and in many cases could only provide uniform amplification at the cost of non-uniform time delay of signals of different frequency known as non-linear phase response characteristic. This invention provides a relatively simple and cheap means of obtaining uniform amplification through a wide band of frequencies and at the same time preserving uniform phase response.

Accordingly, it is one object of this invention to provide an improved wide band amplifier.

Another object of the invention is to provide a simple wide band amplifier having uniform amplification and time delay.

Other objects of my invention will become apparent upon reading the detailed description together with the drawing.

In the drawing, Fig. 1 shows in schematic diagram form, the connections of an amplifier and circuit elements embodying the invention.

While Figs. 2-5 show in circuit diagram form modifications of the embodiment of the invention shown in Fig. 1.

It is known that it is possible to obtain amplification which is independent of frequency within wide limits by means of an amplifying valve whose anode circuit includes a resistance across which the amplified voltage occurs. In such a circuit arrangement there are, however, frequently other impedances that may influence the frequency relation to a greater or less extent. If a screen grid valve is used as the amplifier valve the screen grid conductor generally includes an impedance dependent on frequency which is constituted, for example, by a resistance and a parallel condenser and serves for the securing of the desired screen grid voltage and for smoothing the screening grid voltage from the voltage supply feeding the anode. The alternating voltages to be amplified produce a voltage drop across this impedance which is dependent on frequency and which, due to the control action of the screening grid on the anode current, brings about a voltage

drop across the resistance in the anode circuit which is dependent on frequency. The amplification is consequently dependent on frequency.

The lead connecting the anode and the screen grid to the source from which the anode and screen grid voltages are obtained often includes in addition an impedance, for example the internal impedance of said source, or a resistance with parallel-condenser, which serves for smoothing by-passing or uncoupling. This impedance also influences the variation of the amplifier with frequency.

According to the invention, in order to obtain an amplification which is substantially invariant with frequency in spite of the presence of one or both of the two above-mentioned impedances, the anode circuit of the amplifier valve includes, in series with the anode resistance, impedances which are respectively proportional to the impedance in the screen grid conductor and/or to the impedance in the common conductor by which the anode and the screen grid are connected to the source of voltage.

In addition it is often desirable that the amplifier should be insensitive to potential variations of the source of voltage. According to a further feature of the invention, as will be shown hereinafter, this may be ensured by making the resistance in the anode circuit of the amplifier valve equal to the reciprocal of the slope of the anode current-screen grid voltage characteristic. In this case the impedance in the anode circuit which is proportional to the impedance in the common lead connecting the anode and the screen grid to the source of voltage may be omitted.

Fig. 1 of the drawing shows a schematic diagram of connections of an amplifier embodying the invention. This circuit arrangement comprises an amplifier valve of the pentode type whose screen grid conductor includes an impedance Z_s . The common lead by which the anode and the screen grid are connected to the source of voltage E_a includes an impedance Z_c ; according to the invention the resistance R_a in the anode circuit has connected in series therewith two impedances αZ_s and βZ_c which are proportional respectively to Z_s and Z_c . As may be established by calculation or measurement, the ratio between the amplified voltage e_2 and the unamplified voltage e_1 , or in other words the amplification, is independent of frequency if the proportionality-factors α and β are chosen in accordance with the following conditions:

$$\alpha = R_a / q S_s$$

$$\beta = (1+q) (R_a S_s - 1)$$

q designating the ratio between the screen grid alternating current i_s and the anode alternating current i_a , which ratio may be deemed constant, and S_s designating the slope of the anode current-screen grid voltage characteristic.

If α and β are chosen in accordance with the above equations the amplification is given by the expression,

$$10 \quad \frac{e_2}{e_1} = SR_a$$

where S designates the slope of the anode current-control grid voltage characteristic.

As shown in Fig. 2, the impedances Z_s and Z_c may be constituted respectively, for example, by resistances R_s and R_c with parallel condensers C_s and C_c . In this case, it is necessary for the impedances αZ_s and βZ_c in the anode circuit to be constituted respectively by resistances αR_s and βR_c with parallel condensers

$$\frac{C_s}{\alpha} \text{ and } \frac{C_c}{\beta}$$

For networks of Z_s and Z_c other than those just mentioned the impedances in the anode circuit which are proportional to them may be readily determined in a similar manner.

In order that the circuit arrangement shown in Fig. 1 or 2 may become insensitive to potential variations of the source of voltage E_a , the resistance R_a is preferably made equal to the reciprocal of the slope of the anode current-screen grid voltage characteristic, consequently

$$35 \quad R_a = \frac{1}{S_s}$$

In this case, due to the control action of the screen grid on the anode current, a potential variation of the source of voltage E_a brings about an identical but oppositely directed potential variation at the resistance R_a so that the latter compensates exactly for the former. No potential variations, therefore, occur between the output terminals A_1 and A_2 . This is not altered either when further impedances are included between the terminals A_1 and A_2 , which may be desirable for reducing the total impedance included in the anode circuit, since the proportioning

$$50 \quad R_a = \frac{1}{S_s}$$

often leads to such a high value for R_a that the influence of the anode-cathode capacity of the amplifier valve on the amplification of the higher frequencies is greater than can be conveniently handled. In this case, suitable impedances may be arranged between the terminals A_1 and A_2 so that the total impedance included in the anode circuit is reduced and the influence of the anode-cathode capacity of the amplifier valve consequently decreases.

Such a circuit arrangement is shown in Fig. 3 in which it is premised that the form of the impedance Z_a corresponds to the data above given. An optional impedance Z_1 is connected, in parallel with Z_a , in series with impedances

$$\frac{d}{1-d} Z_a \text{ and } \frac{d}{1-d} Z_1$$

The output voltage e_2 is obtained from the two latter impedances. The factor d is a number less than 1.

The amplification of this circuit arrangement is found to be given by

$$75 \quad \frac{e_2}{e_1} = d S Z_a$$

and if Z_a is consequently chosen in accordance with the above equation this amplification is again independent of frequency.

By suitable choice of the factor d the total impedance included in the anode circuit may be reduced to a value as small as desired so that the influence of the anode-cathode capacity is reduced.

It may be observed that if

$$10 \quad R_a = \frac{1}{S_s}$$

the proportionality factor β becomes equal to zero and the impedance βZ_c is consequently omitted.

The impedances Z_s and Z_c need not always be present in the circuit arrangement at the same time. Thus, for example, it is often possible to omit the impedance Z_c or, if it forms the internal impedance of the source of voltage E_a , to neglect it. In this case, however, it may be desirable to include in the anode circuit an impedance Z_b which is constituted, for example, as usual by a resistance R_b with parallel condenser C_b , as is shown in Fig. 4. Again, as is clearly evident, the amplification is independent of frequency when a proportional impedance

$$\frac{Z_b}{\alpha}$$

is provided in the screen grid circuit.

The impedances Z_b and αZ_s of Fig. 4 are preferably so transformed as to also assist in smoothing the anode voltage. This leads to the circuit arrangement shown in Fig. 5 in which resistances R_1 and R_2 are united with the condensers C_1 and C_2 to form a filter. So far as the frequency relation is concerned, this circuit arrangement is equivalent to that shown in Fig. 4 if R_1 , R_2 , C_1 and C_2 are such that they satisfy the following conditions:

$$40 \quad C_1 = \frac{C_s C_b}{C_s + \alpha C_b}$$

$$45 \quad C_2 = \frac{\left(\frac{C_s^2 R_s}{\alpha} + C_b^2 R_b \right)^2}{\left(\frac{C_s}{\alpha} + C_b \right) (C_s R_s - C_b R_b)^2}$$

$$50 \quad R_1 = \frac{\left(\frac{C_s}{\alpha} + C_b \right)^2 \alpha R_s R_b}{\frac{C_s^2 R_s}{\alpha} + C_b^2 R_b}$$

$$55 \quad R_2 = \frac{(C_s R_s - C_b R_b)^2}{\frac{C_s^2 R_s}{\alpha} + C_b^2 R_b}$$

In the foregoing we assumed the impedances Z_s , Z_c , αZ_s and βZ_c to be associated with the same amplifier stage. It is however, obvious that when the impedances Z_s and Z_c are associated with an amplifier stage different from that with which the impedances αZ_s and βZ_c are associated it is also possible to obtain amplification that is independent of frequency. In this case, the proportionality factors must of course be chosen in accordance with the particularities of the tubes and circuit arrangements in use.

It is also possible simultaneously to compensate, in the anode circuit of an amplifier stage, the influence on the frequency relation of the impedances Z_s and Z_c at the same stage and also of the corresponding impedances at one or more of the preceding and/or following stages.

Having described my invention, what I claim is:

1. A wide band amplifier having uniform

amplification comprising an electron discharge tube having a cathode, a control grid, a screen grid and an anode, a supply source, a connection between the cathode and supply source, a first impedance connected between said screen grid and a second impedance, said second impedance being connected to the cathode through the supply source, an anode circuit comprising a resistor, a third impedance proportional to said first impedance, and a fourth impedance proportional to said second impedance connected in series, and means to impress signal voltage between the control grid and cathode.

2. An amplifier as claimed in claim 1 and wherein the resistance in the anode circuit is substantially equal to the reciprocal of the slope of the anode current-screen grid voltage characteristic of the tube.

3. An amplifier as claimed in claim 1 and where all of said impedances comprise a resistor connected in parallel with a condenser.

4. An amplifier as claimed in claim 1 and comprising in addition, connected in parallel with said anode circuit, a circuit including a fifth impedance connected in series with a sixth and a seventh impedance, said sixth impedance being proportional to said fifth impedance and said seventh impedance being proportional to the total impedance of said anode circuit.

30 5. An amplifier as claimed in claim 1 and wherein said second impedance is zero and comprising in addition, a first auxiliary impedance connected in said anode circuit, and a second auxiliary impedance connected in series with said first impedance, said second auxiliary impedance being proportional to said first auxiliary impedance.

35 6. A wide band amplifier having uniform am-

plification comprising an electron discharge tube having a cathode, a control grid, a screen grid and an anode, a supply source, a connection between the cathode and supply source, a first impedance connected between said screen grid and a second impedance, said second impedance being connected to the cathode through the supply source, an anode circuit comprising a resistor, a third impedance proportional to said first impedance, a fourth impedance proportional to said second impedance connected in series, means to impress signal voltage between the control grid and cathode, and output terminal means connected to said anode and said cathode.

7. A wide band amplifier having uniform 15 amplification comprising an electron discharge tube having a cathode, a control grid, a screen grid and an anode, a supply source, a connection between the cathode and supply source, a first impedance connected between said screen grid 20 and a second impedance, said second impedance being connected to the cathode through the supply source, an anode circuit comprising a resistor, a third impedance proportional to said first impedance, a fourth impedance proportional 25 to said second impedance connected in series, a circuit connected in parallel with said anode circuit comprising a fifth impedance connected in series with a sixth and seventh impedance, said sixth impedance being proportional to said 30 fifth impedance and said seventh impedance being proportional to the total impedance of said anode circuit, means to impress signal voltage between said control grid and said cathode, and output terminal means connected to the junction of said fifth and said sixth impedance and to said cathode.
